UNITED STATES PATENT OFFICE.

LUTHER V. MOULTON, OF GRAND RAPIDS, MICHIGAN.

DESIGN FOR A GARMENT-SUPPORTING LOOP.

SPECIFICATION forming part of Design No. 33,357, dated October 16, 1900.

Application filed March 19, 1900. Serial No. 9,341. Term of patent 14 years.

To all whom it may concern:

Be it known that I, LUTHER V. MOULTON, a citizen of the United States, residing at Grand Rapids, in the county of Kent and State of Michigan, have invented and produced a new and original Design for Garment-Supporting Loops, of which the following is a specification, reference being had to the accompanying drawings, forming part thereof.

Figure 1 is an elevation of a garment-supporting loop, showing my new design; and Fig. 2 is a perspective of the same.

As shown in the drawings, the leading or material features of my design consist in the semicircular middle bend A, the diverging arms B B, and the outwardly-turned eyes C C, the general outline being a triangular figure with open base and rounded angles.

The particular form of my design is that of a continuous piece of round wire having a 20 semicircular middle bend A, slightly-diverging or parallel arms B B, bent outwardly, oppositely, and thence downward in opposite curves, as at D D, and thence turned outward and upward in circular eyes C C. 25

Having described my invention, what I claim as new, and desire to secure by Letters Patent, is—

The design for a garment-supporting loop, as herein shown and described. 30

In testimony whereof I affix my signature in presence of two witnesses.

LUTHER V. MOULTON.

Witnesses:

PALMER A. JONES,
MILES V. EASTERBY.
